UNITED STATES PATENT OFFICE.

RUDOLPH A. MILLER, OF GALVESTON, TEXAS, ASSIGNOR OF ONE-HALF OF HIS RIGHT TO CHARLES NEYNABER, OF SAME PLACE.

WHIFFLETREE.

SPECIFICATION forming part of Letters Patent No. 282,999, dated October 5, 1880.

Application filed January 5, 1880.

To all whom it may concern:

Be it known that I, RUDOLPH A. MILLER, of Galveston, in the county of Galveston and State of Texas, have invented a new and useful Improvement on Swingletrees, of which the following is a specification.

This invention has relation to whiffletrees; and it consists in the features of construction and combination hereinafter fully described, and particularly pointed out in the claim.

Figure 1 is a plan view, partly in section, of a whiffletree embodying my improvements. Fig. 2 is a bottom plan of a portion of the whiffletree, showing the recess in which the base or flanged portion of the detachable eye fits. Fig. 3 is a vertical sectional view taken through the line xx in Fig. 1. Fig. 4 is a plan view of the detachable eye, and Fig. 5 is a side elevation of the same, a portion being broken away.

Referring by letter to the drawings, C designates the whiffletree, made of cast-steel or malleable iron, nearly crescent-shaped, and cored out at B and E to give it lightness. The webs 25 E', left between the openings B and E, give it the requisite strength. The ends are provided with longitudinal openings G, in which screw-bolts H, provided with rings A, are secured by nuts I.

At the center of the whiffletree C an opening or oval-shaped aperture, D, is provided, and the underface of the whiffletree is recessed, as at a, around the aperture D. Bolt-holes d' are made through the whiffletree near the aperture D, as shown in Fig. 2.

A detachable eye, c, provided with a flange, b, constructed to fit the recess a, is provided

with bolt-holes d², corresponding in size and location with bolt-holes d', and is secured in place in the opening D and recess a by nut-bolts d, as shown in Fig. 1.

The front and rear edges of the whiffletree C are rounded, as shown in Fig. 3, in order that the animal's legs may not be cut by coming in contact therewith. The draw-pins of 45 the ears for which this whiffletree is especially adapted pass up through the detachable eye c, and when it has become worn it may be removed and another one substituted, thus prolonging the usefulness of the single-tree for 50 years. This is equally true of the rings A. When broken they may be cheaply replaced.

I am aware that metal whiffletrees composed of two plates separated by a block and riveted together have been used; also, that a whiffletree of wood, with a metal face-plate and a metal eye for the pin, is not new, and I do not broadly claim either of said constructions.

Having thus fully described my invention, what I claim as new, and desire to secure by 60 Letters Patent of the United States, is—

An improvement in whiffletrees, the metal whiffletree C, cored out at B and E, and having the central oval opening, D, in combination with the removable eye c b, secured in the 65 recess a by the bolts d, and the removable rings A A, secured in the openings G by the nuts and bolts H I, substantially as and for the purposes set forth.

RUDOLPH A. MILLER.
